(57) **CLAIM**

The ornamental design for a bulk liquid dispenser, as shown and described.

DESCRIPTION

FIG. 1 is a top plan view of a bulk liquid dispenser showing my new design;

FIG. 2 is a front elevational view thereof;

FIG. 3 is a left side perspective view thereof; and,

FIG. 4 is a right side elevational view thereof.

The broken lines in the drawing depict portions of the bulk liquid dispenser that form no part of the claimed design.
